UNITED STATES PATENT OFFICE.

WILLIAM B. POTTER, OF SCHENECTADY, NEW YORK, ASSIGNOR TO THE GENERAL ELECTRIC COMPANY, OF NEW YORK.

LIGHTNING-ARRESTER.

SPECIFICATION forming part of Letters Patent No. 551,786, dated December 24, 1895.

Application filed August 31, 1895. Serial No. 561,093. (No model.)

To all whom it may concern:

Be it known that I, WILLIAM B. POTTER, a citizen of the United States, residing at Schenectady, in the county of Schenectady, State 5 of New York, have invented certain new and useful Improvements in Lightning-Arresters, (Case No. 266,) of which the following is a specification.

My invention relates to lightning-arresters, 10 and has particular reference to arresters for high-potential circuits, especially for those employing alternating currents.

It has for its object to provide an arrester in which the character of the current will not 15 affect the result and which may be capable of adaptation to any voltage by an extension of the principles involved in its construction for moderate potentials.

As ordinarily constructed, lightning-arresters 20 have been efficacious only upon continuous-current circuits or upon alternating-current circuits of very moderate potentials. A lightning-arrester capable of working with certainty upon potentials of a thousand volts 25 or upward has been practically unknown. This is particularly the case where an inductive load is thrown upon a circuit, in which case, where the self-induction and capacity of the circuit balance each other, a resonant 30 condition may be brought about and the potential may rise very greatly, even to such a point as to arc across the ordinary discharge-spaces or spark-gaps without the intervention of the static discharge. Increasing the size 35 of the parts does not give a corresponding protection, and in practice it has been found impossible to insure protection to lines between which exist electromotive forces of several thousand volts.

40 My invention therefore consists in an arrester provided with a plurality of spark-gaps arranged in series. Each of the spark-gaps is placed in an insulating-chute and is separated from the others in such a manner that 45 it is impossible for the discharge to arc across from one gap to another. In conjunction with the spark-gaps as thus arranged I provide a magnetic blow-out. The coil which I prefer for this blow-out has no iron core. By preference 50 I provide two of these coils, one upon each side of the series of chutes, and so ar-

range them that the lines of force are transverse to the path of the arc, as particularly described in my Patent No. 543,892, issued August 6, 1895. By dispensing with the iron 55 in the core I avoid hysteresis effects, and also prevent the "backing up" or impedance of the discharge, which would tend to force it from the ground-path and compel it to pass through the machine. The coil without iron 60 is not only free from hysteresis effects, but provides a substantially uniform magnetic field, so that a number of arcs formed simultaneously at different gaps in the series will be acted upon with practically equal power. 65 In the arrangement of circuits which I prefer the coil is connected between two of the electrodes forming the series of spark-gaps, so that it is in a shunt to the path of the arc. This arrangement I have found efficacious, 70 the amount of current flowing in the coil being ample for the purposes for which it is designed.

In installing a lightning-arrester of my design it is of course intended to place one in 75 each line, and between each arrester and the machine which it is intended to protect I place an impedance-coil, which is ordinarily composed of a number of turns of the main or feeder in which the arrester may be placed, 80 and by preference has no iron core.

The accompanying drawings show an embodiment of my invention in practical form, Figure 1 being a side elevation with one side removed, showing the interior construction 85 of the arrester. Fig. 2 is a plan view partly in section. Fig. 3 is a diagram of the circuits in the arrester itself. Fig. 4 is a diagram showing the manner of installing it.

In Figs. 1 and 2 A is a base of suitable non-conducting material. B B are supports ordinarily made of metal, designed to support the side pieces C C, which are made of slate or other refractory insulating material. D D are dividing walls between the spark-gaps which 95 are formed between the electrodes E E. By this construction it will be seen that when the two parts or side walls C C are in position the intervening septa D D form with them inclosing chutes, as in my patent before referred to, so that the arc is confined in a small 100 space, and the lines of force from the coils act

energetically upon it. II are the coils, which are formed without an iron core, as already expressed in my statement of invention. Two of these are employed, one upon each side of the arrester. Intervening blocks O O enable the parts B to form a common support for the coils and the side walls of the apparatus.

The circuits will be more readily understood from Fig. 3. N is the terminal connected to line, from which the path of the current is through the coils I, connected to the second of the electrodes E by the lead H'. The lead H passes from the terminal N directly to one of the electrodes. Thus the static discharge will pass directly from the terminal N over the lead H, across the spark-gaps to the terminal G', and from there to ground. The line-current, however, will pass partly over the lead H and partly through the coils I and the lead H', energizing the coils and blowing out the arc at the first air-gap. If the resistance of the series of air-gaps be not sufficient to prevent it, the line-current will follow down the series, but the coils I will remain energized and will blow out the arcs as fast as they form.

Fig. 4 shows the arrangement of the installation. K K are the induction-coils to which I have referred, and m n the lines or mains. L A indicates the lightning-arrester connected between the mains and the ground at G. M is the machine to be protected. The lightning discharge passes along one of the lines, but penetrates with difficulty through the coil K, the self-induction of which tends to prevent the passage of the high-potential alternating-light discharge, and the current, as it is ordinarily expressed, is "backed down" through the lightning-arrester to ground, the arcing across being interrupted by the magnetic field, as already explained.

By the construction which I have described I have been enabled to break arcs upon a potential of ten thousand volts with certainty and without the damaging effects so often noticed in discharges of this character. I

have also been enabled to adjust the lightning-arrester to various potentials by employing various numbers of spark-gaps in series, and so far as my experiments have gone I believe that potentials of any amount may be broken by having a sufficient number of such gaps.

What I claim as new, and desire to secure by Letters Patent of the United States, is—

1. A lightning arrester comprising a number of spark-gaps in series, each gap inclosed in a chute of refractory insulating material, and a common arc-extinguishing means for all of the spark-gaps.

2. A lightning arrester comprising a number of spark-gaps in series, each spark-gap inclosed in a chute, and a common magnetic blow-out for all of the gaps.

3. A lightning arrester comprising a number of spark-gaps in series, each spark-gap inclosed in a chute, and a common magnetic blow-out for all of the spark-gaps composed of coreless coils.

4. A lightning arrester consisting of a number of spark-gaps in series, each spark-gap inclosed in a chute, and a common arc-extinguishing means for the spark-gaps, comprising coils connected between the line terminals and one of the spark-gap electrodes, forming a shunt to the path of the main discharge.

5. A lightning arrester consisting of a number of spark-gaps in series, each spark-gap inclosed in a chute, and a common arc-extinguishing means for the spark-gaps, comprising coreless coils connected between the line terminal and one of the spark-gap electrodes forming a shunt to the path of the main discharge.

In witness whereof I have hereunto set my hand this 27th day of August, 1895.

WILLIAM B. POTTER.
